(57) **CLAIM**

The ornamental design for a spiral wound battery, as shown and described.

DESCRIPTION

FIG. 1 is a front perspective view of an embodiment of a battery in accordance with the present invention. The battery includes terminals on the top, a handle in the center of the top, a flat section on the top half of each of the front and the back, curved portions in the bottom half of each of the front and the back, a horizontally ribbed portion on the top half of each side, and a flared edge portion having rounded corners along the junction between the top of the battery and the main body of the battery.

FIG. 2 is a front view of a battery in accordance with the FIG. 1 embodiment.

FIG. 3 is a top view of a battery in accordance with the FIG. 1 embodiment; and,

FIG. 4 is a side view of a battery in accordance with the FIG. 1 embodiment.
